VENDING MACHINE

Filed July 2, 1925.

Patented May 24, 1927.

1,629,824

UNITED STATES PATENT OFFICE.

ORSON N. KELLY, OF LOS ANGELES, CALIFORNIA.

VENDING MACHINE.

Application filed July 2, 1925. Serial No. 41,082.

This invention relates to vending machines, and particularly to that type of vending machine which is adapted to dispense elongated objects such as pencils, 5 cigars and the like, responsive to the insertion of a proper coin within the said vending machine.

The invention has for an object the provision of a vending machine of the character stated, which is fool-proof as to operation, simple of construction, and not liable to get out of order.

A further object is the provision of a vending machine which is so formed and 10 constructed as to deliver only one article upon the insertion of a coin in the vending machine.

A further object is the provision of a vending machine in which the casing has no 15 visible outside locks.

A further object is the provision of a vending machine which does not require that any direction appear thereon as to its operation.

20 Ordinary vending machines for dispensing gum and the like are notoriously at fault in that the said vending machines may be easily robbed by the insertion of slugs which either operate the machine or prevent 25 its operation. Also, most vending machines are so constructed that a coin is first inserted after which a lever is moved to eject the commodity. The constant working of the lever often discharges more of the commodity than originally intended, and the 30 present invention overcomes these difficulties in that only one commodity can be discharged responsive to the insertion of one proper coin.

35 In practicing the present invention I have provided a suitable casing within which is housed the mechanism of the vending machine proper and the present embodiment of the machine is adapted to dispense pencils. A roller provided with facial axial 40 grooves is controlled by movement of a knob projecting exterior the casing. The knob is free to rotate in either direction without strain on any part of the mechanism and 45 when a coin of proper denomination is inserted within the coin-receiving slot of the casing the knob will lock with the roller and permit the roller to be turned in either direction to eject one of the pencils. After a 50 pencil has been ejected the roller may no longer turn regardless of the turning of

the knob until a further coin is placed in the coin-receiving slot.

The invention has for further objects the provision of a vending machine which is 60 simple of construction and is generally superior to vending machines now on the market.

With the above mentioned and other objects in view, the invention consists in the 65 novel and useful provision, formation, construction, association and relative arrangement of parts, members and features, all as disclosed in the drawings, and finally 70 pointed out in claims.

In the drawing:

Figure 1 is a front elevation of the vending machine;

Figure 2 is a cross sectional view on an enlarged scale and taken on the line 2—2 of 75 Figure 1;

Figure 3 is a cross sectional view on the line 3—3 of Figure 1;

Figure 4 is a cross sectional view on an enlarged scale and taken on the line 4—4 of 80 Figure 2; and,

Figure 5 is a fragmentary detail, taken on the line 5—5 of Figure 1.

Corresponding parts in all the figures are designated by the same reference characters.

85 Referring with particularity to the drawing, the improved vending machine is designated as an entirety and in one embodiment by A, of which a is a coin-receiving chute, 90 b a commodity discharging roller, d means for rendering the roller b operative upon the insertion of a proper coin within the coin chute a, and e means for locking a portion of the vending machine casing f.

95 The casing f is conventional in form having side wall members 1, a detachable back wall member 2, and a front wall member 3, which members 1, 2 and 3 are suitably interconnected through the medium of a base 100 member 4 and a top member 5. The front of the casing is provided with a glass panel 6 so that any commodity within the casing may be readily viewed. It will be noted that the top 5 is flanged as shown at 7 so as 105 to confine the upper portions of the front wall and side wall members, while the back wall member 2 is adapted to bear against the said flange 7 as illustrated at 8 and be locked through the medium of the means e 110 to the said top 5. The bottom member 4 is provided with a flange 9. The lowermost end

of said back wall 2 is tapered as shown at 10 to fit against a tapered portion of the flange 9 and when the said back wall 2 is swung against the flange 7, as shown at 8, the means 5 *e* will lock the back against removal from between the base and the top of the casing. The means *e* includes a spring-actuated bolt 11 which is passed through aligned openings in a pair of projecting studs 12 and 13 on 10 the inner face of the back wall 2. The normal tendency of said bolt is to be urged outwardly from the stud 13 so that the same will engage the flange 7, as shown in Figure 2 at 14. It will be noted that the said bolt 15 is provided with a transverse pin 15 which functions to hold the spring portion of the bolt in position and likewise functions for engagement with a key member shown in dotted lines at 16 in Figure 2. Said bolt is 20 provided with a nose portion so that when the back is closed against the flange 7 the nose will automatically depress the spring-actuated bolt and then snap back of the said flange. The front member 3 is provided 25 with a coin-receiving slot 17, and it is intended that the key 16 should be received through said slot and as the key is curved, as shown at 18, the said key may engage the pin 15 and cam the spring-actuated bolt 11 30 downwardly when the key is pushed inwardly from the dotted line position of Figure 2 so that the bolt will be released from the flange 7. This construction is novel because it is difficult to ascertain just how access to 35 the interior of the casing may be obtained. Furthermore, looking through the coin-receiving slot would not inform a person as to just how the casing might be opened, as it will be noted that the coin-receiving slot 40 is not in alignment with the pin 15 when the bolt is engaging the flange 7. For this reason it is necessary to use a key having a curved end portion. Spaced from one of the end walls 1 is a partition 19 and adapted 45 to be interposed as between the partition 19 and such end wall 1 is the means *d* for rendering the roller means *b* operative. The roller means *b* is mounted upon a shaft 20, one end of such shaft being received in a 50 bearing in the partition 19 and likewise passed through said partition, while the opposite end of said shaft is journaled in a suitable bearing carried by one of the walls 1. Keyed to the shaft 20 is a pair of discs 55 21 and 22 constituting a part of the means *d*. The disc 22 is provided in the present instance with three peripheral notches 23 which are evenly spaced apart as shown in Figure 2, while the disc 21 is of lesser diameter than the disc 22 and is provided with three coin-receiving pockets 24 which are 60 evenly spaced apart. The three coin-receiving pockets 24 provide three segmental portions 25, and each of said segmental portions is provided with a facial arcuate

groove 26, all of which grooves lie in the same curved path. A disc 27 likewise forming a part of the means *d* bears against the disc 21 and said disc 27 is provided with three spaced studs 28 adapted to be received, 70 when the said disc 27 is rotated, within the grooves 26. The said grooves are relatively deep so that the said studs 28 normally project within the said disc 21 at least half or more than half the thickness of said disc. 75 The side wall 1 shown in Figure 4 is provided with a bearing part 29, and a knob 30 carried on a short shaft 31 projects through an opening in the bearing 29 and is keyed as shown at 32 to the disc 27. Thus rotation of the knob 30 will produce rotation of the disc 27. Rotation of the discs 21 and 22 will not occur during this rotation of disc 27, for the reason that a spring-pressed detent 33 carried on a bracket 34 is adapted 80 to be received in some one of the notches 23 on the disc 22 to prevent movement. 85

The roller *b* transversely spans the sides of the casing, that is, it lies between one side wall and the partition 19 and is carried, as has been stated, on the shaft 20. This roller is provided with three peripheral and longitudinal grooves 35 which grooves are evenly spaced apart. The grooves are so formed that the walls bounding the same are straight sided. Likewise carried on the peripheral roller are agitators 36 which consist of narrow segmental portions in which the peripheral surface thereof has a different curvature from the curvature of the roller, the maximum curvature being at practically the center of such segmental portions, the segmental portions then curving downwardly from such maximum point toward the periphery of the roller. A bin portion 37 is immediately above the periphery of the roller which bin portion comprises a pair of plates extending transversely between one of the sides 1 and the partition 19, and which plates are inclined 90 downwardly. The intention of the said bin portion is to direct a commodity, which, in the present instance are pencils 38, on to a portion of the periphery of the roller. An inclined wall member 39 lies transversely 95 within the casing and immediately below the roller, and immediately below the said member 39 and the said roller is a delivery chute 40 which is adapted to direct a commodity 100 from the said casing through a delivery opening 41 adjacent the base of said casing. 105

The coin chute *a* is placed immediately behind the coin-receiving opening 17 and within the casing between the end wall 1 and the partition 19, and in such position as to direct the coin into one of the coin-receiving pockets of the disc 21. This coin chute *a* is so formed as to direct the coin to an inclined portion 42 of such chute which inclined portion is cut away as shown at 110 43. 115

One wall of the said chute is slightly bulged outwardly, as shown at 44 and the cut-away portion 43 terminates in a wider end, as shown at 45. The coin chute is adapted to 5 direct a proper coin at practically right angles to the inclined portion of such chute to the coin-receiving pocket of the disc 21, and such coin-receiving chute terminates with guards 46 and 47 adjacent the periphery of the disc 21.

A pair of guards 48 and 49 are mounted on opposite sides of the roller *b*, the said guards having faces conforming in part to the curvature of the said roller. The purpose of these guards will be explained in the 15 operation. The guard 49 forms a continuation of one of the walls of the bin 37.

The operation of the device just described is as follows: If we assume that a five-cent piece is the proper coin to operate 20 the vending machine, upon insertion of the five-cent piece it will be received in the coin chute which will drop the coin into one of the coin-receiving pockets of the disc 21. It will be noted that one of the coin-receiving 25 pockets is in direct alignment centrally of the delivery end of the coin-receiving chute, as illustrated in Figure 2 at 49. When the coin is so received within the said pocket 30 upon a turning of the knob 30 in either direction, the coin will be engaged by one of the projections 28 on the disc 27, which will push the said coin and rotate the discs 21 and 22 for the reason that the coin is secured 35 within the pocket and is prevented from escaping from said pocket by engaging one or the other of the curved guards 46 or 47. Upon movement of the disc 22 the roller *b* will be rotated and the detent 33 will cam itself out of one of the notches 23. The bin 37 has directed one of the pencils 38 within one of the commodity grooves 35, see Fig. 3, and the roller as it is turned will bring the pencil against the guard 48 which 45 will prevent the said pencil from escaping from the groove 35. The agitators 36 immediately follow and act to cam the pencils already on the bin upwardly so that another pencil will fall into a following groove 50 on the roller. When the roller has turned a distance so that the coin might drop from the coin pocket which would be a position as illustrated in Figure 2 at 50, the guards 46 and 47 terminating adjacent such position 55 so that the coin may be so ejected from the pocket, the following notch 23 will be reached and the spring-pressed detent 33 will fall therein and lock the disc 22 against further rotation. The pencil will drop onto 60 the delivery chute 40 and out through the opening 41. The result will be that the knob 30 will be free to rotate in either direction and the present arrangement will not permit more than one pencil to be delivered 65 at a time. If a smaller coin than

the selected coin should be inserted through the coin-receiving opening, the bulged part 44 would tend to push said coin outwardly at a slight angle, with the result that it would fall out of the coin chute through the 70 cut-away portion 43 thereof. If a coin of the approximate size of the selected coin should be inserted the coin would then fall from said coin chute through the cut-away portion shown at 45.

75

If a very thin coin or slug were inserted in the slot the same would pass through the slot 51, this slot having a width slightly under the width of a proper coin.

When it is desired to re-fill the bin the 80 back 2 of the casing may be readily removed by the insertion of a key through the coin slot 17, as shown in Figure 2 to depress the bolt 11.

The bin 37 is provided with cut-away portions 52 as shown in Figure 5 so that portions of the agitators may project therethrough, and agitate any commodity such as pencils on the bin and within the casing. The feature of having a device which will 85 permit rapid rotation in either direction of the operating knob 30 without in any manner injuring the apparatus, is novel, because the average person will attempt to operate a machine without payment or will tinker with 90 the machine, which often puts the same out of order.

It is obvious that various changes and modifications may be made in practicing the invention, in departure from the particular 100 showing of the drawing, without departing from the true spirit of the invention.

Having thus disclosed my invention, I claim and desire to secure by Letters Patent:

1. In a machine embodying a casing containing coin receiving mechanism, an entrance member to said casing, a narrow coin slot in the casing, a lock for said entrance member within the casing, a coin chute in alignment with the slot and lock, a key insertable through the aligned slot and chute to actuate said lock, said slot and chute constituting guides for the key in its presentation to the lock.

2. A vending machine embodying a display compartment adapted to contain articles to be vended, a closed compartment for coin control mechanism, an entrance member for obtaining access to both of said compartments, a narrow coin slot and chute in said closed compartment, a lock for said entrance member hidden from view in said closed compartment, said coin slot, chute and lock being in alignment, and a key for said lock insertable through said slot and chute and guided thereby in its presentation to said lock.

In testimony whereof, I have signed my name to this specification.

ORSON N. KELLY.
